UNITED STATES PATENT OFFICE

2,553,489

STARTING AND OPERATING DEVICE AND
CIRCUITS FOR ELECTRIC DISCHARGE DE-
VICES

Philippe Waguet, Paris, France, assignor to General Electric Company, a corporation of New York

Application June 19, 1948, Serial No. 34,027
In France December 24, 1946

8 Claims. (Cl. 315—98)

1

This invention relates to electric discharge devices of the type employing ionizable mediums such as gases and vapors, and more particularly to starting and operating devices and circuits thereof.

An object of my invention is to provide new and improved starting and operating circuits for electric discharge lamps.

Another object of my invention is to provide a new and improved starting and operating circuit for fluorescent lamps which eliminates flickering of the lamps due to repeated starting attempts consequent upon failure to ignite.

A feature of my invention is the elimination of the possibility of repeated undesirable starting attempts if, for any reason, a lamp should either fail to start when first switched on, or should thereafter become defective. Thus, if a lamp be defective and fail to start immediately when it is switched on, no further starting attempts, with consequent undesirable flickering, will be made. While the lamp is switched on, if for any reason it should go off, for instance as a result of a lowered supply voltage, the lamp will not attempt to start on the lowered voltage but will simply remain extinguished until a control switch is manually operated.

For a better understanding of my invention reference may be had to the following description taken in connection with the accompanying drawing and its scope will be pointed out in the appended claims. Fig. 1 is a diagrammatic view of an electric discharge device and a starting and operating circuit therefor incorporating my invention, and Fig. 2 illustrates a variation of the circuit shown in Fig. 1.

In accordance with my invention, I have provided a means of eliminating the flickering caused by an electric discharge device attempting to restart, due to the loss of emissive coating on the electrodes or because of variations in operating voltage or any other means creating an unstable condition in the discharge device. In accordance with my invention I have provided a relay which is restrained from returning to its rest position when the discharge lamp is extinguished. Generally speaking, I provide in the magnetic circuit of a starting switch or relay, in addition to the current or control coil which is in series with the lamp, a voltage or holding coil which becomes automatically connected in parallel with the conductors of the distribution system as soon as the control coil is energized by the discharge current. In this manner, if the

2

discharge discontinues for one reason or another, the starting switch is "locked out."

Some of the advantages offered by my invention are as follows: Instantaneous lighting of the lamp without any flickering or beats, elimination of flickering when the lamp becomes defective, lengthening of the life of the lamp due to equal potential filaments used therein.

Referring to Fig. 1, I have there illustrated one embodiment of my invention as applied to an electric discharge device 1. The electric discharge device 1, such as a fluorescent lamp, therein illustrated comprises an elongated tubular or cylindrical envelope 2 having sealed into the ends thereof filamentary electrodes 3 and 4. Filamentary electrodes 3 and 4 may comprise a coil, preferably in the form of a coiled coil of tungsten wire activated with oxides of alkaline earth metals such as a mixture of barium and strontium oxides. The envelope 2 contains a gaseous atmosphere such as a rare gas (like neon, argon or mixtures thereof) at a pressure of a few millimeters and a small quantity of mercury which, during the operation of the lamp, has a low pressure of the order of 10 microns. The device 1 may be a low pressure positive column lamp of a fluorescent type provided with a suitable phosphor or fluorescent coating. This fluorescent coating, upon excitation by the radiation produced by an electric discharge between the electrodes, transforms a shorter wave radiation due to the discharge into longer wave radiation such as radiation within the visible range.

Device 1 is connected across a suitable current supply 5, 5' which, for example, may be a 115 volt 60 cycle source, through a stabilizing resistance or ballast 6 and the filamentary heating windings of transforming means 7. The transforming means 7 comprising a primary winding section 8, a pair of step-down secondary filamentary heating winding sections 9, 9', and a voltage step-up winding 10 which is connected across the current supply 5, 5' through a switching means 11. The unitary relay or switching means 11 may comprise an armature or contactor 12 in series with the primary winding section 8 of transforming means 7 across the current supply, a current or control coil 13 in series with device 1 across the current supply 5, 5' and connected to actuate contactor 12 upon the flow of current through the device, and a second voltage or holding coil 14 connected across the current supply 5, 5' and energized upon actuation of contactor 12. Upon movement of arma-

ture or contactor 12 from position *a* to position *b* due to the magnetic force set up in coil 13 by the passage of discharge current therethrough, coil 14 is connected across the current supply 5, 5'. The magnetic force set up in coil 14 by the passage of current therethrough is adequate to retain contactor 12 in position *b* until the starting and operating circuits are de-energized. A manual make-and-break switch 15 is used to connect device 1 to the current supply 5, 5'. An auxiliary electrode 16 is connected, by means of the low-capacitance condenser 17, to the primary winding section 8 of transforming means 7 through the step-up secondary winding section 10.

The operation of the circuit illustrated in Fig. 1 is as follows: In the rest position, as shown in Figure 1, the contactor 12 of relay or switching means 11 closes the circuit of the primary winding 8 of the transforming means 7. As soon as the switch 15 is closed, the thermo-emissive filamentary electrodes 3 and 4 are heated by the secondary winding sections 9 and 9' and the auxiliary electrode 16 is raised to a suitable potential level by the voltage step-up winding section 10 of the transforming means 7. The device or lamp lights up and the discharge current which passes through the coil 13 of relay or switching means 11 causes that relay to operate, which in turn opens the circuit of the primary winding section 8 of the transformer 7 and applies voltage to coil 14 of that relay which now cooperates with coil 13. The relay remains now in the operated or *a* position as long as the supply switch 15 is closed. If the discharge lamp goes out by itself, the relay can no longer return to the rest position, and any attempt to re-ignite the lamp is suppressed, thus preventing flickering.

Fig. 2 incorporates the same corresponding parts shown in Fig. 1 except that the auxiliary electrode 16 is connected, by means of the low-capacitance condenser 17, directly to one side of the current supply 5, 5'. In this particular circuit the auxiliary electrode 16 has a varying potential which fluctuates as the potential of the current supply 5, 5' changes. The operating of the circuit is, however, identical to that of Fig. 1 except for the starting potential applied to the auxiliary electrode 16.

While certain specific embodiments have been shown and described, it will, of course, be understood that various modifications may be made without departing from the invention. Thus a number of lamps may be connected either in series or in parallel. Various other electrode-heating circuits may be provided, and different types of ballasts may be used with other sources of voltage. The appended claims are, therefore, intended to cover any such modifications falling within the true spirit and scope of the invention.

What I claim as new and desire to secure by Letters Patent of the United States is:

1. Apparatus for operating a gaseous luminous electric discharge device, of the type including a pair of thermionic electrodes, from a voltage source, comprising a pair of input terminals adapted to be connected to said source and opposed pairs of output terminals adapted to be connected to said electrodes, a transformer having a primary winding, and secondary windings respectively connected to said pairs of output terminals, a relay having a control coil, a holding coil, and a two-position contactor, a ballasting impedance, a main circuit constituted by con-

necting said opposed pairs of output terminals, in series with said control coil and said ballasting impedance, across said input terminals, said main circuit being adapted to produce a discharge within an electric discharge device, a starting circuit constituted by connecting said primary winding, in series with said contactor in its inoperated position, across said input terminals, and a holding circuit constituted by connecting said holding coil, in series with said contactor in its operated position, across said input terminals.

2. Apparatus for operating a fluorescent lamp, of the type including a pair of thermionic electrodes and an auxiliary starting electrode located intermediate the ends thereof, from a voltage source, comprising a pair of input terminals adapted to be connected to said thermionic electrodes, and an auxiliary output terminal adapted to be connected to said auxiliary electrode, a transformer having a primary winding, a pair of secondary windings and an auxiliary secondary winding, connections from said pair of secondary windings to said opposed pairs of output terminals in order to provide heating current to the thermionic electrodes of an electric device, a connection from one side of said auxiliary winding to one of said output terminals, and from the other side to said auxiliary output terminal, a relay having a control coil, a holding coil, and a two position contactor, a ballasting impedance a main circuit constituted by connecting said opposed pairs of output terminals, in series with said control coil and said ballasting impedance, across said input terminals, a control circuit constituted by connecting said primary winding, in series with said contactor in its inoperated position, across said input terminals, and a holding circuit constituted by connecting said holding coil, in series with said contactor in its operated position, across said input terminals.

3. Apparatus for operating a fluorescent lamp of the type including a pair of thermionic electrodes and an auxiliary starting electrode located intermediate the ends thereof, from an alternating voltage source, comprising a pair of input terminals adapted to be connected to said source, opposed pairs of output terminals adapted to be connected to said thermionic electrodes, and an auxiliary output terminal adapted to be connected to said auxiliary starting electrode, a transformer having a primary winding, a pair of secondary windings connected respectively to said opposed pairs of output terminals in order to provide heating current to the thermionic electrodes of a lamp, and an auxiliary secondary winding connected to said auxiliary output terminal, a relay having a current control coil, a voltage holding coil, and a contactor occupying a first position in its inoperated state and a second position in its operated state, said relay requiring current, substantially equal to the discharge current of said lamp, through said control coil to operate said contactor, and said relay requiring only voltage, substantially equal to the source voltage, across said holding coil to maintain said contactor in its operated state, a ballast impedance, a main circuit constituted by connecting said opposed pairs of terminals, in series with said control coil and said ballast impedance, across said input terminals, a control circuit constituted by connecting said primary winding, in series with said contactor in its first

or inoperated position, across said input terminals, and a holding circuit constituted by connecting said holding coil, in series with said contactor in its second or operated position, across said input terminals.

4. Apparatus for operating a fluorescent lamp of the type including a pair of thermionic electrodes and an auxiliary starting electrode located intermediate the ends thereof, from an alternating voltage source, comprising, a pair of input terminals adapted to be connected to said source, opposed pairs of output terminals adapted to be connected to said thermionic electrodes, and an auxiliary output terminal adapted to be connected to said auxiliary starting electrode, a transformer having a primary winding, a pair of secondary windings connected to said opposed pairs of output terminals for providing heating current to the thermionic electrodes of a lamp, and an auxiliary secondary winding connected between one of said opposed pairs of output terminals and said auxiliary output terminal, a relay having a current control coil, a voltage holding coil, and a contactor carried by a magnetic armature coacting with both said coils, said contactor occupying a first position in its inoperated state and a second position in its operated state, said relay requiring current, substantially equal to the discharge current of said lamp, through said control coil to operate said contactor, and said relay requiring only voltage, substantially equal to the source voltage, across said holding coil to maintain said contactor in its operating state, a ballasting impedance, a main circuit constituted by connecting said opposed pairs of output terminals, in series with said control coil and said ballasting impedance, across said input terminals, a control circuit constituted by connecting said primary winding, in series with the first position terminals of said contactor, across said input terminals, said contactor operating upon the initiation of current through said output terminals to open said control circuit, and a holding circuit constituted by connecting said holding coil, in series with the terminals of said contactor in its second position, across said input terminals, said contactor completing said holding circuit in its operated state, and locking in said state to prevent a return to said inoperated state consequent upon failure of current to flow through said output terminals.

5. In combination, a gaseous luminous discharge device, of the type including a pair of thermionic electrodes, a voltage source, a transformer having a primary winding and secondary windings connected to said thermionic electrodes, a relay having a control coil, a holding coil, and a two-position contactor, a ballasting impedance, a main discharge circuit constituted by connecting said device, in series with said control coil and said ballasting impedance across said source, a starting circuit constituted by connecting said primary winding, in series with said contactor in its inoperated position, across said source, and a holding circuit constituted by connecting said holding coil, in series with said contactor in its operated position, across said source.

6. In combination, a fluorescent lamp of the type including a pair of thermionic electrodes and an auxiliary starting electrode located intermediate the ends thereof, a voltage source, a transformer having a primary winding, a pair of secondary windings, and an auxiliary secondary winding, connections from said pair of second-

ary windings to said thermionic electrodes for providing heating current thereto, a connection from one side of said auxiliary winding to one of said thermionic electrodes, and from the other side to said auxiliary electrode, a relay having a control coil, a holding coil and a two-position contactor, a ballasting impedance, a main discharge circuit constituted by connecting said lamp through its thermionic electrodes, in series with said control coil and said ballasting impedance, across said source, a control circuit constituted by connecting said primary winding, in series with said contactor in its inoperated position, across said source, and a holding circuit constituted by connecting said holding coil, in series with said contactor in its operated position, across said source.

7. In combination, a fluorescent lamp of the type including a pair of thermionic electrodes and an auxiliary starting electrode located intermediate the ends thereof, an alternating voltage source, a transformer having a primary winding, a pair of secondary windings connected to said thermionic electrodes to provide heating current thereto, and an auxiliary secondary winding connected to said auxiliary electrode, a relay having a current control coil, a voltage holding coil, and a contactor occupying a first position in its inoperated state and a second position in its operated state, said relay requiring current, substantially equal to the lamp discharge current, through said control coil to operate said contactor, and said relay requiring only voltage, substantially equal to the source voltage, across said holding coil to maintain said contactor in its operated state, a ballasting impedance, a main discharge circuit constituted by connecting said lamp, in series with said control coil and said ballasting impedance, across said source, a control circuit constituted by connecting said primary winding in series with said contactor in its first or inoperated position, across said source, and a holding circuit constituted by connecting said holding coil, in series with said contactor in its second or operated position, across said source.

8. In combination, a fluorescent lamp of the type including a pair of thermionic electrodes and an auxiliary starting electrode located intermediate the ends thereof, an alternating voltage source, a transformer having a primary winding, a pair of secondary windings connected to said thermionic electrodes to provide heating current thereto and an auxiliary secondary winding having one side connected to one of said thermionic electrodes and the other side connected to said auxiliary electrode, a relay having a current control coil, and a contactor carried by a magnetic armature coacting with both said coils, said contactor occupying a first position in its inoperated state and a second position in its operated state, said relay requiring current, substantially equal to the lamp discharge current, through said control coil to operate said contactor, and said relay requiring only voltage, substantially equal to the source voltage, across said holding coil to maintain said contactor in its operated state, a ballasting impedance, a main discharge circuit constituted by connecting said lamp, in series with said control coil and said ballasting impedance, across said source, a control circuit constituted by connecting said primary winding, in series with the first position terminals of said contactor, across

said source, said contactor operating upon the initiation of a discharge through said lamp to rupture said control circuit, and a holding circuit constituted by connecting said holding coil, in series with the terminals of said contactor in its second position, across said source, said contactor completing said holding circuit in its operated state and locking in said state to prevent a return to said inoperated state consequent upon failure of a discharge to occur within said lamp.
